METHOD OF AND MACHINE FOR FORMING END CAPS FOR COIL PACKAGES

George E. Mirfield, Youngstown, Ohio, assignor
to The Youngstown Sheet and Tube Company,
Youngstown, Ohio, a corporation of Ohio

Application May 18, 1938, Serial No. 208,555

18 Claims. (Cl. 93—36)

This invention relates to the formation from a flat strip of fibrous material of individual pieces of annular conformation and substantially U-shaped cross-section particularly intended for use in packaging hollow cylindrical articles in the manner disclosed in my copending application for U. S. Letters Patent entitled "Shipping package for hollow cylindrical articles", Serial No. 206,356, filed May 6, 1938.

- 19 As explained therein the packaging of hollow cylindrical articles, such as coils of metal strip or the like, to protect them from moisture and corrosion has heretofore embodied certain difficulties which are overcome by the use of the invention thereof. The package produced thereby includes end caps of annular conformation and substantially U-shaped cross-section made from creped, preferably substantially waterproof paper such as that known as "kraft" paper, and the machine of my present invention is particularly adapted for forming these caps.

The principal object of the invention, therefore, is to provide a machine for progressively converting a flat strip of fibrous material to substantially U-shaped cross-section and curvilinear form to facilitate the production of these annular end caps and generally similar articles.

30 A further object is to provide a machine including forming mechanism and means for continuously feeding a strip of expansible fibrous material, such as paper, thereto while progressively scoring and stretching parts of the moving strip to facilitate the forming operation so that when the formed strip attains a suitable length it 35 may be severed and the formed section utilized as an end cap.

Another object is to provide a method of progressively operating upon a strip of expansible fibrous material or the like to impart to it an annular configuration and U-shaped cross-section for the production of end caps adapted for use in packaging hollow cylindrical articles or for other purposes.

45 Other objects, purposes and advantages of the invention will hereinafter more fully appear or will be understood from the following description of a machine constructed in accordance therewith, adapted for the performance of the method contemplated thereby and illustrated in 50 the accompanying drawings in which:

Fig. 1 is a front elevation of the machine with a strip of the fibrous material passing through it;

Fig. 2 is a side elevation of the machine viewed from the right in Fig. 1 with certain parts broken away to more clearly illustrate its construction;

Fig. 3 is a side elevation of the machine viewed from the left in Fig. 1;

Fig. 4 is a fragmentary enlarged bottom plan view partly in horizontal section of the forming rolls and adjacent parts;

Fig. 5 is a fragmentary front elevation showing a part of the machine with a length of formed strip extending therefrom; and

Fig. 6 is a fragmentary section on the line 6-6 in Fig. 5.

In the several figures like characters are used to designate the same parts and the relative thickness of the strip of fibrous material is exaggerated for clearness of illustration.

Referring now more particularly to the drawings, the machine embodies a frame 1 which supports its several operating parts and may comprise a heavy upstanding plate adjacent the lower edge of which is a bracket 2 carrying a spindle 3 adapted to receive a roll P of the fibrous material which is to be formed by the machine, expandible or creped "kraft" paper usually being suitable for the purpose. Bracket 2 also supports an idle roller 4 over which the strip of paper drawn from the roll passes in its travel through the machine. The paper moves upwardly from the roller 4 along a substantially vertical path adjacent a heater 5 including edge guides 6 and comprising a heating unit (not shown) preferably electrically energized, so as to progressively warm the paper as it passes over the unit and thereby soften the waterproofing compound with which it is impregnated, this compound usually being a thermoplastic material of an asphaltic nature. Above the heating unit are positioned a pair of rollers which draw the paper from the roll and prepare it for subsequent forming. These rollers, generally designated R, R' are supported from brackets 10 and 11 which are carried by the frame and secured thereto through the medium of angles 12 and 13 bolted to the frame and to the brackets respectively, the frame being apertured in the vicinity of the rollers and brackets to provide clearance for these and other parts. Roller R is supported from brackets 10, 11 on a shaft 14 which also carries a spur gear 15 meshing with a similar gear 16 secured to a sleeve 17 carrying roller R' and in turn supported by a shaft 18 carried in brackets 10, 11. The portions of this shaft which extend through the brackets are eccentric with respect to its intermediate portion on which sleeve 17 is located and at one end beyond the adjacent bracket a hand lever 19 is secured to the shaft so that by means of the lever the shaft can be moved generally toward or away

from roller R to vary the clearance between the rollers R, R'. Bracket 11 where it supports shaft 18 is split and supplied with a screw 20 whereby it may be constricted against the shaft to lock the latter in its rotatively adjusted position.

Roller R comprises a cylindrical surface 25 and a frusto-conical surface 26 adjacent thereto provided with axially spaced projecting ribs 27 complementary to corresponding grooves 28 in a somewhat similar frusto-conical portion of roller R' hereinafter more fully described, roller R' also having a cylindrical surface 29 aligned with the cylindrical surface 25 of roller R.

The frusto-conical portion of roller R' is built up of several parts including a number of rings 30 the outer surfaces of which are generally frusto-conical and of progressively larger external diameter in a direction receding from cylindrical surface 29 so that the rings when assembled together substantially conform to the frusto-conical surface 26 of roller R, the edges of the rings being beveled off to form grooves 28. These rings, which are of equal internal diameter, are rotatably mounted on a sleeve 31 held in place by a collar 32 secured on sleeve 17 with the result that the rings can rotate on sleeve 31 independently of each other and independently of cylindrical portion 29 of roller R'.

Shaft 14 carrying roller R and, through gears 15, 16, the cylindrical portion 29 of roller R' are driven by bevel gears 33, 34 respectively mounted on shaft 14 and a shaft 35 journaled in a bracket 36 secured on the frame; the latter shaft is driven from a suitably positioned motor 37 through worm gearing 38, 39 and in addition to driving gear 33 the shaft also carries and drives a sprocket 40 the purpose of which will hereinafter more fully appear.

Adjacent the upper part of frame 1 is a forming die 45 secured by bolts 46 to the face of the frame and, as most clearly shown in Fig. 6, this die is provided with a substantially U-shaped slot 47 which imparts to the strip a corresponding U-shaped cross-section after its passage between rollers R, R'.

On the opposite side of the die from these rollers are arranged arcuate guides 50, 51 which are curved on different radii from the same center to provide a substantially semi-circular path extending along the face of frame 1 from die 45, the outer guide 51 being desirably interrupted a short distance beyond the die to afford space for a pair of feeding rollers 52, 53. Upper roller 52 is rotatable on a shaft 54 in turn eccentrically journaled in the frame and in a bracket 55 carried thereby and the lower roller 53 is mounted on a stub shaft 58 journaled in bracket 55. Shaft 54 extends beyond the bracket and is provided at its outer end with a hand lever 59 so that by moving the latter the roller 52 by reason of the eccentric mounting of the shaft can be moved towards or retracted from roller 53 to vary the clearance between them. The shaft 58 carries a sprocket 56 interconnected by a chain 57 with sprocket 40 to thereby drive shaft 58 and roller 53 secured thereto, and shaft 54 carries a spur gear 60 adapted to mesh with a like gear 61 attached to the end of roller 53 for rotation with shaft 58 so that the two rollers are driven at the same speed when the gears are in mesh.

Operation

This machine is desirably used in a manner now to be described for continuous formation of coil package end caps and is adapted to operate

automatically substantially without attention of the operator except to cut off the formed strip into suitable lengths as it progressively leaves the machine.

With the roll of paper or other fibrous material P in position on the spindle 3 as indicated in the drawings, to initiate the machine operation the leading end of the strip is first led under idle roller 4, then upwardly past heater 5, between rollers R, R' and through forming die 45, which imparts the U-shape of its pass to the strip. The end of the shaped strip is then led between guides 50, 51 with one side of the U extending between rollers 52, 53 which assist in feeding it along the guides.

During these operations rollers R, R' and 52, 53 are preferably separated by manipulation of hand levers 19, 59 as far as possible to facilitate threading the end of the strip between them, and rollers R, R' are then so adjusted that their cooperative cylindrical surfaces 25, 29 grip the paper fairly tightly with the result that when they are rotated in opposite directions by the driving mechanism energized by motor 37 they draw the strip of paper upwardly from roller 4 and the ribs 27 on roller R then cooperate with grooves 28 on roller R' to produce a plurality of score lines s in the paper as it passes between them, after having been softened by heat from heater 5 during its passage to the rollers. As has been explained, roller R is of solid construction while the conical portion in roller R' is made up of a plurality of relatively movable rings which are not positively driven although the cylindrical portion 29 of this roller is so driven; the speed of that part of the strip passing between the cylindrical surfaces of the rollers therefore corresponds substantially to their peripheral speed but the adjacent part of the strip passing between the frusto-conical surfaces is driven at progressively slower speeds corresponding to the progressively slower peripheral speed of the frusto-conical surface of roller R as its diameter decreases, the rings of roller R' operating at differential speeds inversely proportional to their diameters, due to the larger rings being in engagement with those parts of the strip which are driven by the smaller diameter portions of roller R. Thus the several parts of the strip move at varying speeds in accordance with the part of roller R which they contact and as the part driven from the cylindrical surfaces of the rollers moves at the highest speed, it is severely stretched relatively to the other parts, that driven by the conical surface is also stretched but to a progressively lesser degree, depending on the differential speeds at which it is driven, and the edge part not contacted by either roller R or R' remains substantially in its original unstretched condition.

Thus as the strip moves from rollers R, R' toward the forming die its most severely stretched part is of greater length than the remainder of the strip and can readily be folded normal to the scored part of the latter on the outside of a curve while the wholly unstretched part is of less length than the scored part and can be similarly folded on the inside of a curve on the same center but of smaller radius, the edge score lines s' insuring regularity of these lines of fold.

After enough of the strip has been drawn through the forming die by rollers 52, 53 and by them then fed between the guides 50, 51 to complete an end cap of the desired diameter the strip is severed, preferably on the delivery side of the rollers to avoid the necessity of rethread-

ing its leading end therethrough, usually a sufficient amount of the strip being allowed for each end cap to permit the ends of the annulus forming it to overlap slightly to facilitate its subsequent use in packaging coils as described in my said copending application.

It will be apparent from the foregoing that the operations performed on my machine as herein described are characterized principally by

- 10 a rather severe stretching of a part of the strip adjacent one edge while a part preferably of generally corresponding width adjacent the other edge remains unstretched and the intermediate part is differentially stretched substantially to
- 15 the extent required to enable it to assume an annular shape without other material deformation after it has passed the stretching rollers. Moreover, I have found that the formed strip does not appreciably tend to depart from the
- 20 shape imparted to it during its passage through the machine due largely to the fact that before it is stretched the waterproofing composition with which it is impregnated has been softened as the strip moves past the heater and remains
- 25 more or less in that condition until the strip leaves the forming die so that as the strip subsequently cools the hardening of the composition assists in thereafter maintaining it in the shape to which it has been brought.

30 It will be appreciated that the end caps which the machine is designed especially to produce are applied over the ends of a hollow cylindrical coil of sheet metal or the like and that in practice these coils are usually formed on mandrels 35 of predetermined diameter, for example 22", but in accordance with the gage of the metal and the number of linear feet in the coil the thickness, that is, the difference between the lengths of the inner and the outer radii of the coils may vary.

40 Thus, for example, if the thickness of a given coil is 2", the distance between the inner and the outer walls of an end cap designed for application thereto should be approximately 2" whereas if the thickness of the coil is 4", the distance 45 between the inner and outer walls of the cap should likewise approximate 4". As this distance is primarily determined in the formation of the caps by the spacing between the scores on which the strip is folded in the die, it will be

50 apparent that caps suitable for different thicknesses of coils may be formed on the machine by using strip stock of different widths and different sizes of dies adapted to fold it on any two selected scores. In the drawings the machine is 55 shown as set up to form a cap for a coil of maximum thickness as the die is arranged to fold the strip on the outermost of the scores formed by rollers R, R' but its adaptability for forming caps for coils of lesser thickness will be readily understood in the light of what has just been said.

I have herein referred more particularly to the use of the machine for making end caps for use in packaging coils of sheet or strip metal but it is of equal utility for forming generally similar 65 annular pieces of fibrous material of substantially U-shaped cross-section designed for other uses, and as the services of an attendant are required only for cutting the strip to suitable length from time to time as it is progressively formed, the machine can be operated very economically and the end caps produced at a cost but little in excess of that of the strip stock.

70 While I have herein described my invention with considerable particularity, it will be understood that I do not desire or intend to limit or

confine myself thereby in any way, as changes and modifications in the form, structure and arrangement of the several parts of the machine as well as in the several steps of the method contemplated by the invention will readily occur to those skilled in the art and may be made if desired without departing from the spirit and scope of the latter as defined in the appended claims.

Having thus described my invention, I claim 10 and desire to protect by Letters Patent of the United States:

1. A machine of the character described comprising means for progressively moving an expansible strip of fibrous material and simultaneously stretching an edge part thereof to elongate said part relatively to the remainder of the strip and means for forming the stretched strip to substantially U-shaped cross section.

2. A machine of the character described comprising means for progressively longitudinally stretching an edge part of a moving strip of sheet material, means for concurrently differentially stretching another part of the strip and means for then forming the strip to substantially U-shaped cross section and imparting generally annular configuration thereto.

3. A machine of the character described comprising means for progressively warming a moving strip of expansible sheet material, means for progressively longitudinally stretching a part of the warmed strip adjacent one edge thereof while maintaining the part adjacent the opposite edge relatively unstretched, and means for then progressively forming the strip to substantially U-shaped cross section.

4. A machine of the character described comprising means for progressively warming a moving strip of expansible sheet material, means for progressively stretching a part of the warmed strip adjacent one edge thereof while maintaining the part adjacent the opposite edge relatively unstretched, and means for progressively differentially stretching the intermediate part of the strip between said edge parts, the extent of said differential stretching varying in substantial proportion to the distance from said unstretched part.

5. A machine of the character described comprising means for progressively scoring a moving strip of stretchable sheet material to thereby segregate by longitudinal scores three parts of the strip and stretching the part between one score and an edge of the strip substantially uniformly while maintaining the part between the other score and the opposite edge substantially unstretched and means for concurrently differentially stretching the intermediate part of the strip.

6. A machine of the character described comprising a roller having a cylindrical surface and a conical surface progressively receding from adjacent one end thereof, a second roller having cylindrical and conical surfaces respectively cooperative with those on the first roller, means for driving said rollers in engagement with an elongated strip to thereby progressively and differentially stretch different parts of the strip, and means adapted to then form the strip to substantially U-shaped cross section.

7. In a machine of the character described comprising a roller having a cylindrical surface and a conical surface progressively receding from adjacent one end thereof, a second roller having a cylindrical surface cooperative with the

- 5 cylindrical surface of the first roller and a series of relatively rotatable frusto-conical rings cooperative with the conical surface of the first roller and means supporting the rollers for rotation in engagement with a strip of sheet material.
- 10 8. In a machine of the character described comprising a roller having a cylindrical surface and a conical surface progressively receding from adjacent one end thereof and a plurality of axially spaced circumferential ribs projecting from said latter surface, a second roller having a cylindrical surface cooperative with the cylindrical surface of the first roller and a plurality of relatively rotatable frusto-conical rings cooperative with the conical surface of the first roller, the edges of adjacent rings being beveled to form grooves adapted to receive the circumferential ribs of the first roller and means supporting the rollers for rotation in engagement with a strip of sheet material.
- 15 9. In a machine of the character described comprising a roller having a cylindrical surface and a conical surface progressively receding from adjacent one end thereof, a second roller having a cylindrical surface cooperative with the cylindrical surface of the first roller and a series of relatively rotatable frusto-conical rings cooperative with the conical surface of the first roller, means supporting the rollers for rotation in engagement with a strip of sheet material and means for driving the rollers to thereby feed the strip between them and stretch an edge portion thereof during its passage between their cylindrical surfaces and differentially stretch the adjacent portion between their conical surfaces.
- 20 10. A machine of the character described comprising a roller having a cylindrical surface and a conical surface progressively receding from adjacent one end thereof, a second roller having a cylindrical surface cooperative with the cylindrical surface of the first roller and a series of relatively rotatable frusto-conical rings cooperative with the conical surface of the first roller, means supporting the rollers for rotation in engagement with a strip of sheet material, means for driving the rollers to thereby feed the strip between them and stretch an edge portion thereof during its passage between their cylindrical surfaces and differentially stretch the adjacent portion between their conical surfaces and means disposed adjacent the rollers adapted to progressively form the strip after its passage between them into an annulus of substantially U-shaped cross section.
- 25 11. A machine of the character described comprising a roller having a cylindrical surface and a conical surface progressively receding from adjacent one end thereof, a second roller having a cylindrical surface cooperative with the cylindrical surface of the first roller and a series of relatively rotatable frusto-conical rings cooperative with the conical surface of the first roller, means supporting the rollers for rotation in engagement with a strip of sheet material, means for driving the rollers to thereby feed the strip between them and stretch an edge portion thereof during its passage between their cylindrical surfaces and differentially stretch the adjacent portion between their conical surfaces, means disposed adjacent the rollers adapted to progressively form the strip after its passage between them into an annulus of substantially U-shaped cross section and guiding means providing an arcuate path to receive the formed strip.

12. In a machine of the character described, a pair of rollers rotatable on parallel axes, one of said rollers having a cylindrical surface and a frusto-conical surface rigid therewith and the second roller having a cylindrical surface aligned with the cylindrical surface of the first roller, means coaxial with the second roller and rotatable relatively thereto providing a plurality of relatively movable frusto-conical surfaces respectively substantially aligned with portions of the conical surface of the first roller and means for rotating the rollers in engagement respectively with opposite faces of a moving strip of sheet material.

13. In a machine of the character described a pair of rollers rotatable on parallel axes, one of said rollers having a cylindrical surface and a frusto-conical surface rigid therewith and the second roller having a cylindrical surface aligned with the cylindrical surface of the first roller, parallel shafts respectively supporting the rollers for rotation with their cylindrical surfaces in engagement with opposite faces of a strip of sheet material, means supported from and rotatable about the shaft carrying the second roller providing a series of frusto-conical surfaces cooperative with the frusto-conical surface of the first roller to engage other portions of the sheet, driving means for the rollers and means adapted to receive the moving strip after its passage between the rollers and progressively form it to substantially U-shaped cross section.

14. In a method of forming end caps for hollow cylindrical packages, the steps of progressively moving an elongated strip of expansible sheet material and concurrently relatively severely stretching one edge part of the strip longitudinally while maintaining the opposite edge relatively unstretched and then progressively forming the strip to substantially U-shaped cross section.

15. A method of treating an elongated strip of expansible sheet material which comprises the steps of progressively warming the strip, progressively longitudinally stretching a part of the warmed strip adjacent one edge while maintaining a part adjacent the opposite edge relatively unstretched and concurrently differentially stretching the strip between said stretched and unstretched parts, then forming the strip to substantially U-shaped cross section.

16. A method of treating an elongated strip of expansible sheet material which comprises the steps of progressively warming the strip, progressively longitudinally stretching a part of the warmed strip adjacent one edge while maintaining a part adjacent the opposite edge relatively unstretched and concurrently differentially stretching and scoring the strip parallel with said edges between said stretched and unstretched parts, then forming the strip to substantially U-shaped cross section.

17. In a method of forming end pieces for packages for hollow cylindrical articles the steps of progressively concurrently differentially stretching a part of the strip between its edges, severely stretching a part adjacent one of the edges while maintaining a part adjacent the opposite edge relatively unstretched and longitudinally scoring the strip between adjacent parts, then progressively forming the stretched and scored strip to substantially U-shaped cross section and imparting arcuate configuration thereto and finally subdividing the strip to form successively a plu-

rality of pieces of substantially annular configuration.

18. In a method of forming end pieces for packages for hollow cylindrical articles the steps of progressively longitudinally scoring a strip of expansible sheet material to segregate the strip into three defined zones, stretching one zone adjacent an edge of the strip longitudinally substantially uniformly, stretching an adjacent zone 10 of the strip transversely differentially and progressively less in substantial proportion to the

distance from the score defining said zone from the adjacent stretched zone, progressively forming the partially stretched strip to substantially U-shaped cross section while imparting arcuate configuration thereto and finally at spaced points longitudinally of the strip severing it transversely to produce successive substantially annular pieces of the material of substantially U-shaped cross section. 5

GEORGE E. MIRFIELD. 10
